UNITED STATES PATENT OFFICE.

ROBERT Z. FARMER, OF BISBEE, ARIZONA.

MECHANISM FOR CONVERTING RECIPROCATING INTO ROTARY MOTION.

1,116,810.

Specification of Letters Patent. Patented Nov. 10, 1914.

Application filed November 26, 1913. Serial No. 803,220.

To all whom it may concern:

Be it known that I, ROBERT Z. FARMER, citizen of the United States, residing at Bisbee, in the county of Cochise and State 5 of Arizona, have invented certain new and useful Improvements in Mechanism for Converting Reciprocating Into Rotary Motion, of which the following is a specification, reference being had to the accompanying drawings.

This invention relates to mechanism for converting reciprocating into rotary motion and has for its primary object to provide a device for this purpose wherein the full 15 power of the reciprocating element is utilized and waste of energy overcome.

The invention has for another of its objects to provide a pair of shafts, a ratchet fixed upon each shaft, a gear wheel provided 20 with dogs to engage the ratchet, a pair of racks connected to the reciprocating element and engaging the respective gear wheels, said gear wheels being alternately locked upon the respective ratchets by said pawls 25 in the reciprocating movement of the racks in opposite directions, a driven shaft, and means for transmitting motion from said first named shafts to the driven shaft constantly in one direction.

The invention has for a further object to produce a mechanism of the above character which is comparatively simple in its construction, is highly durable and efficient in practical use and may be manufactured at 30 small cost.

With the above and other objects in view as will become apparent as the description proceeds, the invention consists in certain constructions, combinations and arrangements of the parts that I shall hereinafter 40 fully describe and claim.

For a full understanding of the invention, reference is to be had to the following description and accompanying drawings, in 45 which—

Figure 1 is a top plan view illustrating the preferred construction of my invention; Fig. 2 is a section taken on the line 2—2 of Fig. 1; Fig. 3 is an enlarged detail section 50 taken on the line 3—3 of Fig. 1; Fig. 4 is a section taken on the line 4—4 of Fig. 1; Fig. 5 is an enlarged detail fragmentary section of one of the ratchets and gear mounted thereon; Fig. 6 is a detail side elevation of one of the collars which is fixed 55

upon the power shaft; Fig. 7 is an enlarged detail section illustrating the mounting of the inner ends of the shafts; Fig. 8 is a detail side elevation of the guide member for the reciprocating racks; Fig. 9 is a detail 60 section taken on the line 9—9 of Fig. 1.

Referring in detail to the drawings, 5 designates a base of any suitable construction upon which the standards 6 are arranged. Additional bearing standards 7 are 65 arranged at opposite sides of the base and in these standards the outer ends of shafts 8 are journaled. These shafts are mounted in the standards 6. It will be observed that one of said shafts is provided with a reduced 70 inner end which is telescopically engaged in a socket provided in the opposed end of the other shaft, as clearly indicated at 9 in Fig. 7. Upon each of the shafts 8 a ratchet 10 is keyed or otherwise secured, said ratchet 75 being held against longitudinal movement by suitable collars 11 arranged upon opposite sides of the ratchet and secured to the shaft by suitable screws 12. Each of the collars is provided with an annular flange 80 13 which is adapted to engage in a recess 14 provided in the face of a gear 15. These collar flanges serve to retain the gear in place and to hold the same against longitudinal movement with respect to the shaft. 85 In the inner wall of the gear 15, a plurality of locking pawls or dogs 16 are pivotally mounted, said dogs being normally held by means of the springs 17 with their free ends in engagement with the teeth 10' of the 90 ratchet 10. It is to be understood that the ratchet teeth and the locking pawls 16 upon one of the shafts 8 project in an opposite direction relative to the pawls and the teeth on the other of said shafts.

18 designates the piston of a gas engine or other power producing machine and to said piston, a forked bar 19 is suitably secured. To each of the arms of this bar, one end of a rack bar 20 is fixed, the lower face 100 of said bar being provided with teeth 21. These rack bars engage with the respective gears 15 and rotate the same in the reciprocating movement of said racks. In order to hold the teeth of the rack bars in engagement with the gear teeth, I provide the member 22 which is provided adjacent its ends with spaced flanges 23. Between these flanges the rack bars 20 are movably disposed, said flanges extending downwardly 110

upon opposite sides of the gears 15. The guide member 22 is suitably secured to the upper ends of the standards 6.

Each of the collars 11 is provided at the 5 juncture of the flange 13 with the body of said collar, with a semi-circular series of apertures 24 through which a suitable lubricant is supplied to the shaft 8. It will be understood from reference to Fig. 3 that 10 the lubricant is applied to the inner faces of the guide flanges 23 so as to facilitate the movement of the rack bar and eliminate friction of said flanges upon the gears 15. This lubricant flows inwardly as indicated 15 by the arrows and finally enters the outer ends of the inclined openings 24 whereby the same is directed to the shaft.

Additional standards 25 are mounted upon the base 5 in which the ends of the driven 20 shaft 26 are journaled. This shaft is provided with a suitable belt wheel 27 which is traversed by the belt 28 extending to the machine which it is desired to operate. One end of the driven shaft is provided with a 25 gear 29 which meshes with a large gear 30 fixed upon one of the shafts 8. The other end of the shaft 26 has a sprocket wheel 31 fixed thereto which is connected by means of the chain 32 to a similar sprocket wheel 33 30 upon the other shaft 8.

From the above description taken in connection with the accompanying drawings, it is believed that the construction and manner of operation of my improved motion 35 converting mechanism will be clearly and fully understood. In the operation of the piston 18, the racks 21 are reciprocated and in their movement in one direction, one of the shafts 8 is positively rotated with respect to the 40 other shaft, the gear 15 thereon being in locked engagement with the ratchet 10. As the other gear wheel is loose, the same will be rotated by the rack which is engaged therewith with respect to the associated 45 ratchet. Thus, the shaft which is rotated by the longitudinally moving rack bar transmits motion to the shaft 26 through the medium of the chain 32 or the gears 29 and 30, as the case may be, while the other of 50 said shafts is rotated in the opposite direction. Upon the reverse longitudinal movement of the rack bars 21, the rotation of the shafts 8 is also reversed, and the gear 15 which was previously loose upon the shaft 55 is now locked therewith through the medium of its pawls 16 and the ratchet 10. Thus, by a direct longitudinal thrust of the rack bars, I positively impart a constant rotary motion to the shaft 26 and utilize 60 substantially the entire power of the reciprocating piston 18 for this purpose, the respective rack bars 20 alternately operating through the medium of the shafts 8 to rotate the power shaft 26.

65 It will be appreciated from the above

that my improved mechanism while of very simple construction is highly efficient in practical operation and may be economically operated. While I have shown and described the preferred construction and arrangement of the several parts employed, it will be obvious that the invention is susceptible of considerable modification therein and I therefore reserve the right to resort to all such legitimate changes as may be 70 fairly embodied within the spirit and scope of the invention, as claimed.

Having thus described the invention, what is claimed is:

1. In mechanism of the character described, the combination of a pair of independently rotatable shafts having their longitudinal axes in alinement with each other, a power shaft, gearing connecting the opposite ends of the power shaft to the respective 85 first named shafts whereby the power shaft is rotated in one direction upon the alternate rotation of the first named shafts in opposite directions, a reciprocatory member, spaced racks connected to said member, 90 gears mounted upon each of the first named shafts and connected by the respective racks, and means for locking the gears upon the respective shafts in the reciprocating movement of the racks in opposite directions. 95

2. In mechanism of the character described, the combination of a pair of shafts having alined longitudinal axes, the end of one shaft telescoping in the opposed end of the other shaft, a power shaft, gearing connecting the opposite ends of the power shaft to the respective first named shafts, whereby said power shaft is constantly rotated in one direction by the reverse alternate rotation of the first named shafts, a ratchet fixed upon each of said first named shafts, a gear mounted upon each of said ratchets, means fixed upon the shaft to prevent longitudinal movement of the ratchets thereon and to hold the gears against longitudinal movement with respect to the ratchets, locking means carried by the gear for engagement with the teeth of the ratchet to lock the gear thereto in its movement in one direction, a reciprocating member, spaced 110 racks connected to said member and engaged with the respective gears, and guide members for said racks to retain the same in engagement with the gears whereby said first named shafts are alternately rotated 115 in reverse directions upon the opposite reciprocating movements of said racks.

3. In mechanism of the character described, the combination of a pair of shafts having their longitudinal axes alined, a power shaft, gearing connecting the opposite ends of the power shaft to the respective first named shafts whereby the power shaft is constantly rotated in one direction 125 upon the alternating reverse rotations of 130

the first named shafts, a ratchet fixed upon each of the first named shafts, a gear mounted upon each of said ratchets, spring pressed dogs carried by the gear for engagement with the ratchet teeth whereby the gears are locked upon the respective shafts to rotate the same in opposite directions, reciprocating racks engaged with the respective gears, a guide member having spaced pairs of depending flanges extending upon opposite sides of the respective gears and holding the same against movement longitudinally of the shaft with respect to the ratchet.

15 4. In mechanism of the character described, the combination of a pair of shafts having aligned longitudinal axes, a power shaft geared to each of said first named shafts, whereby the power shaft is constantly rotated in one direction by alternating reverse rotation of the first named shafts, a ratchet fixed upon each of the first

named shafts, collars secured upon the shafts upon opposite sides of the ratchets, each of said collars having an annular flange, and a plurality of inclined openings at the base of the flange for the feed of a lubricant to the shafts, a gear mounted upon each of the ratchets, the faces of the gear being recessed to receive the collar flanges, reciprocating racks engaged with the respective gears, means carried by the gears for locking the same upon the respective ratchets in the movement of the racks in opposite directions, and a guide member for said racks having spaced pairs of depending flanges extending upon opposite sides of the respective gears.

In testimony whereof I hereunto affix my signature in the presence of two witnesses.

ROBERT Z. FARMER.
